(57) **CLAIM**

The ornamental design for a box spring cover, as shown and described.

DESCRIPTION

FIG. 1 is a perspective view of a box spring cover showing my new design;

FIG. 2 is another perspective view thereof;

FIG. 3 is another perspective view thereof;

FIG. 4 is a front elevational view thereof;

FIG. 5 is a rear elevational view thereof;

FIG. 6 is a left side elevational view thereof;

FIG. 7 is a right side elevational view thereof;

FIG. 8 is a top plan view thereof;

FIG. 9 is a bottom plan view thereof;

FIG. 10 is a front elevational view of the box spring cover

where the box spring cover is in a configuration of use; and,

FIG. 11 is an enlarged view of portion 11 shown in FIG. 1.

The broken lines in the drawings depict portions of the box
spring cover that form no part of the claimed design.**1 Claim, 11 Drawing Sheets**FIG. 1

FIG. 2

FIG. 3

FIG. 4

FIG. 5

FIG. 6

FIG. 7

FIG. 8

FIG. 9

FIG. 10
